UNITED STATES PATENT OFFICE.

HUGH C. EDMISTON, OF ORANGE, NEW JERSEY.

DESIGN FOR A MATCH-BOX AND CANDLE-HOLDER.

42,318.

Specification for Design.

Patented Mar. 19, 1912.

Application filed December 11, 1911. Serial No. 665,159. Term of patent 7 years.

To all whom it may concern:

Be it known that I, HUGH C. EDMISTON, a citizen of the United States, residing at Orange, Essex county, New Jersey, have invented a new, original, and ornamental Design for a Match-Box and Candle-Holder, of which the following is a specification.

In the drawings, Figure 1 is a plan view of a holder embodying my design, Fig. 2 is an end view thereof, and Fig. 3 is a side view thereof.

I claim:

The ornamental design for a match box and candle holder as shown.

In testimony whereof I have affixed my signature in the presence of two witnesses.

HUGH C. EDMISTON.

Witnesses:

LOUIS MEYER,
A. F. TEPE.
